RAILWAY HOPPER CONSTRUCTION

Victor Willoughby, Ridgewood, N. J., assignor to
American Car and Foundry Company, New
York, N. Y., a corporation of New Jersey

Application January 14, 1941, Serial No. 374,311

6 Claims. (Cl. 105—282)

This invention relates to hoppers in general and in particular to hoppers for railway use in which the discharge from the hopper is controlled by sliding doors.

For the handling of sugar, cement or other commodities which must be kept dry both during transit and while discharging, special cars and containers with slide doors have been built, but in all such cars or containers the trackway upon which the door slides has been exposed to the discharging lading with the result that the material accumulated on the slide-way often became caked and hardened and prevented the operation of the door. It is an object of the present invention to provide a new and improved slide door and operating mechanism which will prevent contact of the discharging lading with the slide-ways.

A further object of the invention is the provision of a two-part hopper outlet frame for sliding doors in which the slide-ways may be readily removed for replacement or repair.

A further object of the invention is the provision of a new and improved frame for hopper discharge outlets which may be readily fabricated out of standard shapes and plates.

These and other objects of the invention will be apparent to persons skilled in the art from a study of the following description and accompanying drawings, in which

Figure 1 is a half end and half sectional elevational view of the container having the improved door and frame applied thereto;

Fig. 2 is a half side and half central sectional elevational view of the container hopper with the improved door applied thereto;

Fig. 3 is a half plan view with part in section and taken on line 3—3 of Fig. 2;

Fig. 4 is an enlarged sectional view through the hopper and door operating mechanism of Figure 1 but showing the door in open position;

Fig. 5 is a plan view of the improved door and operating mechanism with the door in closed position;

Fig. 6 is an enlarged plan view of the hopper frame which supports the door;

Fig. 7 is a sectional view similar to Fig. 4 showing a modification thereof and with the view taken on line 7—7 of Fig. 8;

Fig. 8 is a plan view of the modified form and taken on line 8—8 of Fig. 7;

Fig. 9 is a sectional view taken substantially on line 9—9 of Fig. 7, and

Fig. 10 is an end view of the winding mechanism used to control the door.

Referring now to the drawings in detail, it will be seen immediately that the improved hopper frame and slide door of Figures 1 to 6 inclusive have been shown as applied to a less than carload lot container, while the slightly modified form of Figures 8 to 10 inclusive has been shown as applied to a more or less standard railway hopper car. It is, of course, obvious that either door and its operating mechanism

5 could be applied to either a container or to a railway hopper car of more or less standard design.

In Figures 1 to 6 inclusive the less than carload lot container is shown as built up of angle uprights 2, joined together by corrugated sheets 4, joined together at the top by a top closure sheet 6, having an opening therein adapted to be closed by a door 8. The lower edges of the corrugated sheets are joined together by downwardly converging hopper outlet forming sheets 10 which are suitably braced to prevent distortion by angle shape stiffener plate 12. The hopper outlet frame may be made separately and attached to the hopper sheets or, as shown in 15 the present case, the hopper sheets may of themselves form a part of the frame. As clearly shown, the discharge frame is formed by welding flat bars 14 to the lower edge of the hopper forming sheets and suitably bracing these bars 20 to the hopper sheets by gussets 16, thus a hopper discharge opening is formed surrounded on all four sides by an upper frame having the lower surface disposed in substantially a horizontal plane.

25 The lower part of the hopper discharge frame is formed in the present instance by side pieces or slide-ways 18 formed of Z bars with the upper flange adapted to contact and be fastened to the bars 14 by any suitable means such as bolts 19. The lower flange of the Z-shaped slide-ways is directed inwardly and has the major portion of the flange clipped away, thus forming a short ledge or shelf 20 upon which the door slide rails may slide. The slide-ways 30 may terminate at the back edge of the hopper or, as in the present instance, they may extend beyond the hopper back edge for attachment to the container frame, with such attachment accomplished by means of supporting gussets 21. The slide-ways are connected together adjacent the back edge of the hopper discharge opening by means of a flat bar 22 extending between 35 and attached to the inturned flanges of the slide-ways, all as clearly shown in Fig. 4. This bar 40 is located in the plane of the inturned flanges 45

and has attached thereto, as by welding, an angle member 23 having one leg disposed vertically and the other leg directed rearwardly and attached to the upper bar 14 by any suitable means such as bolts 24. The angle member 23 must not extend through for contact with the web of the Z-shaped slideways but must terminate in spaced relation thereto in order to accommodate the door slide rails later to be referred to. It will also be seen from Figs. 4 and 6 that the flat bar 22 is formed with projections or ledges 26 projecting into the discharge outlet opening in order to support a portion of the door when in closed position. The slide-ways are further joined together by means of a flat bar 27 welded or otherwise secured to the inturned flanges of the Z-shaped slideways and this bar is located, as clearly shown in Fig. 4, in the plane of the flanges and in spaced relation to the upper part of the hopper discharge frame. At the forward or operating mechanism side of the hopper the slide-ways must be extended a distance at least equal to the hopper opening and as clearly shown in the drawings the slide-ways have been so extended and are tied into the container structure by means of bracing gussets 28.

The slide door is formed of long side or slide rails 30 joined together at their forward, intermediate and rear portions by vertically extending bars 32, 33 and 34 respectively. The forward and intermediate bars, as well as parts of the slide rails are tied together by upper and lower door plates 36 and 37 respectively, with the upper or load supporting plate reinforced against bending by means of centrally disposed angles 38 (Figs. 2 and 5). The angles 38, together with the upper and lower door plates, form a housing for a screw 40 welded or otherwise secured to the intermediate bar 33 and adapted to be engaged by an internally threaded sleeve 42 terminating in an outer combined thrust collar and operating end 43 rotatably supported in a bracket 44 carried by the container frame. The sleeve 42 is of sufficient length as to always protect the threads of the screw 40, as is clearly shown in Fig. 5.

From the preceding description it will be seen that the hopper frame is made in two parts, the upper of which is readily welded to or becomes a part of the hopper itself, while the lower part is removable for renewal or repair of the slide-ways; also removal of the lower part facilitates assembly of or removal of the door from the structure. In assembling the construction the pre-fabricated door, together with its operating mechanism, will be dropped into position on the lower part of the hopper frame and with the slide rails resting upon the inturned flanges 20 of the slide-ways and with the open part of the door having the slide rails located between the ends of angle 23 and the webs of the slide-ways. After the door has been so positioned in the lower part of the hopper frame the combined door and lower frame may be bolted or otherwise secured to the hopper upper frame. With the door and frame in assembled position and the door closed, as shown in Figs. 1 and 5, rotation of the sleeve 42 will draw the bar 33 toward the operator and, since this bar 33 forms an integral part of the door, the door plates and long slide rails will move along the inturned flanges 20 of the trackway or slide-ways toward the operator. Such movement will continue until rear cross bar 34 of the door contacts a part of the frame, as clearly shown

in Fig. 4. With the door in this open position the slide rails 30 still completely cover and protect the slide-ways at the outlet opening and prevent any material contacting the slide-ways, while intermediate door bar 33 forms the fourth side of the discharge outlet, thus giving a fully controlled discharge from the hopper without any possibility of material contacting any portion of the surfaces supporting or guiding the door. When the direction of rotation of the sleeve 42 is reversed the door plates and entire door structure will be forced toward a closed position in which the bar 33 and lower door plate will be supported upon projecting ledges 26 of frame bar 22. It will, of course, be obvious that the lower door plate may be dispensed with if desired since it does not contact any lading but merely serves to brace and stiffen the upper plate and the lower edges of the slide rails.

Referring now to the modified form shown in Figs. 7 to 10 inclusive, it will be seen that the modified door and frame has been attached to the discharge end of hopper sheets 50 which are part of a more or less standard railway car having customary center sills 52. In this form the hopper discharge frame is again formed in two pieces but so designed as to permit prefabrication of the upper part of the frame. This upper frame part is formed with inclined plates 54 welded together and to a vertically extending plate 56, with all of the plates welded to substantially horizontally disposed bars 58 and with all of the plates properly gusseted or braced by gussets 60. It will be seen that the pre-fabricated upper discharge frame is thus substantially the same as that used in connection with the less than carload lot container shown in Figs. 1 to 6 inclusive. The lower hopper discharge frame is formed by slide-ways or trackways 62 of general Z formation with the upper outwardly directed flanges bolted or otherwise secured as at 63 to the upper frame and with the inturned flanges clipped to provide short supporting ledges or slide-ways 66. These slide-ways project a considerable distance on either side of the hopper discharge opening and are joined together adjacent their rear ends by an angle brace and stop 67. Likewise, the slide-ways are joined together adjacent the rear edge of the discharge opening by means of a flat bar 68 welded or otherwise secured to the flanges 66 of the slide-ways and having secured thereto an inclined plate or bar 69 which in turn is secured to an overlapping angular portion of a bar 70. The ends of bars 69 and 70 are spaced from and free of contact with the web of the slide-ways, but the upper portion of plate or bar 70 is adapted to be bolted or otherwise secured to the upper hopper frame member. An angular plate 72 is provided adjacent the forward side of the hopper and is bolted as at 73 to the upper frame member and extends between the slide rails of the door later to be described.

The slide door is formed as clearly shown of slide bars or slide rails 76 joined together adjacent their forward and rear ends by angle bars 78 and 79 respectively. The intermediate portions of the slide bars or slide rails are joined together by means of door plate 80 which is welded to the lower edge of the slide rails and has attached thereto a cross bar 82 of square or other shape adapted to engage the back surface of angular plate 72, thereby preventing entrance of moisture at the forward edge of the door. As clearly shown in Fig. 7, the rear edge of the door is adapted to

fit beneath the edge of plate 70 and abut plate 69, thereby sealing the closing edge of the door.

In order to operate the door a clevis 84 is attached to the forward edge thereof and is connected to a chain 86 which wraps around an idler pulley or sheave 88 and around a driving pulley or sheave 90 to be again anchored to the door by a U bolt or other means attached to cross bar 78 of the door. The idler pulley 88 and driving pulley 90 are carried upon shafts supported in any suitable manner by the extended portions of the slide-ways which are in turn braced from the car structure by bracing gussets 92. In order to drive the pulley 90 it is fixed upon its shaft and the shaft is extended laterally beyond the outer trackway and has attached thereto the operating head 94 adapted to receive a removable operating bar or rod. In most instances railway hopper cars where carrying cement or other commodities discharge into bins or screwed conveyors through the medium of flexible boots preventing contamination of the discharging material. In order to attach such boots to the present frame, it is only necessary to weld small angles 96 to the lower frame adjacent one side and end of the hopper discharge opening and to weld a bar 97 to the outer edge of one of the slide-ways as clearly shown in Fig. 9. In this way the frame at the upper end of the flexible boot may be supported by angles 96 on two sides and be clamped at the other two sides to bars 97 and 68.

In assembling the improved door and door frame, the upper part of the door frame will be attached to the hopper discharge sheets, after which the preassembled door may be lowered into the preassembled lower part of the frame with the door slide rails overlapping the ends of angle plates 69 and 70. The angle plate 72 is bolted or otherwise secured to the upper hopper frame, after which the preassembled door and lower frame are raised into position and bolted fast, with the slide rails of the door lapping the ends of angle plate 72. The operating mechanism may now be attached by merely fastening the chain at its ends to the door with the intermediate portions wrapped around idler 88 and drive pulley 90. With the door in closed position rotation of the drive pulley in a counter-clockwise direction as viewed in Fig. 7 will cause tension to be placed in the chain 86 and through clevis 84 the door will be pulled toward the idler pulley 88. In the meantime the chain passing over drive pulley 90 will be fed out so that cross bar 78 of the door may move. Full operation of the drive pulley will cause the door to assume a fully open position with cross bar 78 contacting the outer portion of the hopper discharge frame and with the door plate located free of the discharge opening and beneath drive pulley 90, the slide rails will always be riding upon in-turned flanges 66 of the slide-ways and at no time will these slide-ways be exposed to the lading discharging through the hopper outlet. Therefore, there can be no material on the slide-ways to cake or harden and prevent easy operation of the door at all times.

It will be obvious from the preceding descriptions that either type of door frame and door may be used on either the less than carload lot container or upon the standard rail car hopper and without departing in the least from the spirit of the invention. It will also be obvious that various modifications and rearrangements of

parts, other than those shown and described, may be made without departing from the scope of the invention as defined by the following claims.

5. What is claimed is:

1. In a railway hopper structure the combination of a door frame secured to the hopper forming sheets and providing a discharge outlet, said frame being formed by an upper part rigidly connected to the hopper sheets and by a lower part removably secured to the upper part on at least three sides thereof, said lower part being constructed with oppositely directed slideways extending beneath and to at least one side of the discharge outlet, said slideways being joined together intermediate their ends by stop means connected to said upper part, a door slidably carried by said slideways and including a horizontally extending door plate of a width sufficient to close the discharge outlet and bear against said stop means, and vertically extending strips secured to the side edges of said door plate and supporting said plate upon the slideways, said strips being of a length substantially twice the width of the door plate whereby said slideways will be covered by said strips at all times irrespective of the door plate position.

2. In a railway hopper structure the combination of a door frame secured to the hopper forming sheets and providing a discharge outlet,

30 oppositely arranged slideways forming a part of said frame, a door slidably carried by said slideways and comprising vertically spaced apart door plates of a width sufficient to close the discharge outlet, vertically extending slide rails secured to the side edges of the door plates and joining said plates together, said slide rails being of a length substantially twice the width of the door plates, means secured to said door and hopper structure and operable to shift said slide rails along said slideways whereby said door may open or close said discharge outlet, said slide rails covering the portions of the slideways beneath the discharge outlet at all times and irrespective of the door position.

3. In a railway hopper structure the combination of a door frame secured to the hopper forming sheets and providing a discharge outlet, oppositely arranged slideways forming a part of

50 said frame and joined together by stop means projecting into the path of movement of the door, a door slidably carried by said slideways and comprising in part a door plate of a width sufficient to bear against said stop means and close the discharge outlet, slide rails secured to the side edges of the door plate and normal to the plane thereof and of a length substantially greater than the width of the door plate, means secured to the door and hopper structure and operable to move said slide rails along the slideways past said stop means to open and close the discharge outlet, said means including screw means wholly housed by the door structure from contact with the hopper contents, and said slide rails stiffening the door plate and protecting said slideways at the discharge outlet from contact with the hopper contents at all times irrespective of the door position.

4. In a railway hopper structure the combination of a door frame secured to the hopper forming sheets and providing a discharge outlet, oppositely arranged slideways forming a part of said frame, a door slidably carried by said slideways and comprising spaced apart door plates, slide rails joining said door plates together along

their side edges, said slide rails extending normal to the planes of the door plates thereby forming a box section door, said door plates being of a width sufficient to close the discharge outlet and said slide rails being of a length substantially twice the width of the door plates, means secured to said door and hopper structure and operable to shift said slide rails along said slideways whereby said box section door may open or close said discharge outlet, said means including a screw rod located within said box section door and protected from contact with the lading, said slide rails covering the portions of the slideways beneath the discharge outlet at all times and irrespective of the door position.

5. In a railway hopper structure the combination of a door frame secured to the hopper forming sheets and providing a discharge outlet, oppositely arranged slideways forming a part of said frame, a door slidably carried by said slideways and comprising spaced apart door plates joined together along their side edges by vertically extending slide rails, horizontally spaced angle members interposed between said door plates intermediate said slide rails and forming a housing together with the door plates, a screw rod in said housing, a sleeve secured to said hopper structure and engaging said screw rod to move said door from closed to open position, said door plates being of a width sufficient to close the discharge outlet and said slide rails being

of a length substantially twice the width of the door plates whereby said slide rails will cover the portions of the slideways beneath the discharge outlet at all times and irrespective of the door position.

6. In a railway hopper structure the combination of a door frame secured to the hopper forming sheets and providing a discharge outlet, said frame being formed by an upper part rigidly connected to the hopper sheets and by a lower part removably secured to the upper part on at least three sides thereof, said lower part being constructed with oppositely directed slideways extending beneath and to at least one side 10 of the discharge outlet, said slideways being joined together intermediate their ends by stop means connected to said upper part, a door slidably carried by said slideways and including a horizontally extending door plate of a width sufficient to close the discharge outlet and bear 15 against said stop means, and vertically extending strips secured to the side edges of said door plate and supporting said plate upon the slideways, said strips being of a length substantially twice the width of the door plate whereby said 20 slideways will be covered by said strips at all times irrespective of the door plate position, and chain and sprocket means secured to the door and hopper structure to open and close the discharge 25 outlet.

30 VICTOR WILLOUGHBY.
